DESIGN.

H. C. BRILL.

CURRY COMB.

No. 13,099.

Patented Aug. 1, 1882.

UNITED STATES PATENT OFFICE.

HENRY C. BRILL, OF SOUTHBURG, CONNECTICUT, ASSIGNOR TO THE SOUTHBURG CUTLERY COMPANY, OF SAME PLACE.

DESIGN FOR A CURRY-COMB.

SPECIFICATION forming part of Design No. 13,099, dated August 1, 1882.

Application filed May 6, 1882. Term of patent 14 years.

To all whom it may concern:

Be it known that I, HENRY C. BRILL, a citizen of the United States, residing at Southbury, in the county of Hartford and State of Connecticut, have invented and produced a new and original Design for Curry-Combs, of which the following is a specification, reference being had to the accompanying drawings, forming part thereof, in which—

15 Figure 1 is a plan view of my newly-designed curry-comb. Fig. 2 is a side elevation, and Fig. 3 is a front elevation, of the same.

The back A, the comb-bars, and the wooden handle B are substantially the same as in ordinary curry-combs. The shank *a* of the handle B is curved, as shown. The finger-handle C has its body perforated at several points, as shown; but said perforations are not intended to form a part of the design, and may be 20 changed in form or omitted at pleasure. This

finger-handle is rounded and hollowing, substantially in the form of a drawer-pull, and in length it extends substantially the whole width of the comb, where it terminates in the points *bb*. The outer edge of this handle, when viewed 25 from one side, slants toward the handle B, and from this outer edge it rounds over downward to the back A of the comb, as shown most clearly in Fig. 2.

I claim—

30 The design for a curry-comb, substantially as shown and described, the same consisting of the back A and the finger-handle C, the latter having the hollowing and rounded form extending from its outer edge over to the back 35 of the comb.

HENRY C. BRILL.
